RENEWABLE FUSE PLUG

Emile P. Brus, Kansas City, Mo.

Application September 4, 1942, Serial No. 457,283

9 Claims. (Cl. 200—130)

This invention relates to electrical fuse plugs of the removable type and has for its primary object to provide such a plug with a group of specially designed parts for holding a fusible element so as to renew the same when necessary, all without destroying or discarding the said parts of the fuse plug assembly.

One of the most important objects of this invention is to provide an electrical fuse plug with an unique assembly of parts, one of which is a fusible element, renewable by merely removing a specially designed threaded contact post, which post serves as the medium of maintaining all of the component parts of the plug in their operative position.

Minor objects of the invention are particularly important and include specific details of construction, all of which will be made clear during the course of the following specification, referring to the accompanying drawing wherein:

Fig. 1 is an end elevational view of a renewable fuse plug, made in accordance with the present invention.

Fig. 2 is a longitudinal central sectional view through the renewable fuse plug, taken on line II—II of Fig. 1.

Fig. 3 is a composite stretch-out perspective view showing the component parts of the fuse plug.

Fig. 4 is a cross sectional view taken on line IV—IV of Fig. 2.

Fig. 5 is a cross sectional view taken on line V—V of Fig. 2; and

Fig. 6 is a stretch-out plan view of the fusible element forming a part of the plug.

Fuse plugs having renewable fusible elements have been heretofore designed and placed on the market, but in most instances, the same do not meet the stringent requirements of authorities and commercial use, and further, fail because of faulty structure and part design. It is also understood that many fuse plugs having renewable elements have been produced but found ineffective because of complicated parts, and the objectionable amount of time and work required to disassemble and assemble the plug when replacing the fusible element.

It is the prime object of this invention therefore, to produce a screw plug for the conventional fuse box 6 that may be removed from said box, when necessary to have the fusible element 8 renewed, and thereafter, quickly taken apart and reassembled with a fresh fusible element.

The plug comprises a thimble-shaped body 10, preferably produced of glass or other transparent

material in order that the user may readily observe when element 8 has been melted. Element 8 is provided with a partial coating of substance 12, which, when dispersed by heat, will create a colored coating on the inner surface of body 10.

External threads 14 on body 10 cooperate with threaded cylinder 16, made of conducting material, and provided with an inturned annular flange 18, overhanging the lip of body 10, as illustrated in Fig. 2. Flange 18 has an integral, ring-shaped boss 17 on the free marginal edge thereof, the upper face of which is roughened to provide teeth against which the later described perforated plate 30 rests when the parts are assembled.

15 The undulated annular side wall of cylinder 16 not only serves to engage the threads 14 of body 10, but presents threads to enter the socket formed in fuse box 6.

A plug 19 of insulating material has a longitudinal bore 20 and a transverse laterally disposed cavity 22. Longitudinal bore 20 and cavity 22 intersect, as clearly shown in Fig. 2, and for the purpose hereinafter specified. Plug 19 has an annular external flange 24 at one end thereof 25 and a boss 26 on the upper surface, which surface is a part of plug 19 projecting outwardly from within thimble-shaped body 10 when the component parts of the plug are assembled.

20 A notch 28 formed in flange 24 terminates on a plane with a flattened area 21 on the annular periphery of plug 19, to receive a portion of the length of flexible element 8 when it is wrapped about the plug. Another flattened area 23, diametrically opposite to 21 is engaged by another portion of the length of element 8 as shown in Fig. 2. A third flat face 25 on plug 19 lies against a complementary flattened portion 27 on the inner face of body 10.

25 Perforated plate 30 of insulating material overlies boss 17 of cylinder 16 when threaded contact post 32 is moved to place.

30 Flexible element 8 has a nut 34 secured to that end thereof which projects into cavity 22. This nut is of conventional character and in commercial practice, may be soldered directly to the end of element 8 so that the screw-threaded opening 36 thereof lies in alignment with bore 20 when element 8 is in the operative position as regards plug 19. Resilient clip 29 fitted into cavity 22 35 frictionally grips nut 34 and prevents accidental escape of the nut as well as to hold the same in alignment with bore 20 when the innermost portions of the nut and cap are engaged (Fig. 4). The other end of element 8 has an annulus 38 40 created thereon to circumscribe boss 26. When

annulus 38 is in such position, with respect to boss 26, displacement cannot occur and flange 13 of cylinder 16 will be pressed directly against one face of annulus 38 by force exerted on plate 30 by contact post 32. Reference to Fig. 2 indicates how plate 39 is received by the roughened upper surface of boss 17 and how the height of this boss precludes plate 39 from engaging the top of boss 26 on plug 19.

Flange 24 of plug 19 lies between flange 18 and the lip of body 10, and as post 32 is turned into threaded engagement with opening 36 of nut 34, all of the fuse plug parts will be drawn together with positive electrical contacts where most needed. The contact between cylinder 16 and annulus 38 is maintained by the full force of post 32 and no danger of loosening is present. Due to the roughened surface on boss 17, plate 39 cannot turn as post 32 is either tightened or loosened. As the post is turned, plug 19 is held against rotation with respect to body 10 by flattened areas 25 and 27. The contact between post 32 and nut 34 is ample in view of the screw-threaded relation between the parts, and therefore, a definite electrical connection is established between the contact members of box 6 when the fuse is in place, as shown in Fig. 2.

It is obvious from the foregoing that one may very quickly remove and disassemble the entire fuse plug, replace a melted fuse element 8, and again position the plug without creating the danger of wrong connections.

Not only is a fuse plug embodying this invention efficient, easy to manipulate, and desirable from the users' standpoint, but may be made at very low cost, both as regards material and labor.

Minor changes might be made to present fuse plugs having physical characteristics different from those illustrated and described, and it is therefore, desired to be limited only by the spirit of the invention and scope of the appended claims.

Having thus described the invention, what is claimed as new and desired to be secured by Letters Patent is:

1. A fuse plug of the character described comprising a hollow body of insulating material; a plug of insulating material projecting into the hollow body and provided with two intersecting bores; a fusible element partially circumscribing the plug and having one end thereof extending into one bore of the plug and the other end disposed against the outer portion of the plug; a cylinder of conducting material in telescoping relation with the body and bearing against a length of the fusible element at the said other end thereof; a perforated plate of insulating material; and a contact post of conducting material fitted through the perforation of the plate, into the other bore and into engagement with the fusible element.

2. A fuse plug of the character described comprising a hollow body of insulating material; a plug of insulating material projecting into the hollow body and provided with two intersecting bores; a fusible element partially circumscribing the plug and having one end thereof extending into one bore of the plug and the other end disposed against the outer portion of the plug; a cylinder of conducting material in telescoping relation with the body and bearing against a length of the fusible element at the said other end thereof; a perforated plate of insulating material; and a contact post of conducting material fitted through the perforation of the plate into the

other bore and into engagement with the fusible element, said fusible element and the contact post being in screw-threaded engagement whereby upon rotation of the post, said plate is drawn against the cylinder to grip the one end of the fusible element between the cylinder and said plug.

3. A fuse plug of the character described comprising a hollow body of insulating material; a plug of insulating material projecting into the hollow body and provided with two intersecting bores; a fusible element partially circumscribing the plug and having one end thereof extending into one bore of the plug, and the other end disposed against the outer portion of the plug; a cylinder of conducting material in telescoping relation with the body and bearing against a length of the fusible element at the said other end thereof; a perforated plate of insulating material; and a contact post of conducting material fitted through the perforation of the plate, into the other bore and through the fusible element, said contact post and fusible element being in screw-threaded engagement whereby to removably anchor the element in position.

4. A fuse plug of the character described comprising a hollow body of insulating material; a plug of insulating material projecting into the hollow body and provided with two intersecting bores; a fusible element partially circumscribing the plug and having one end thereof extending into one bore of the plug and the other end disposed against the outer portion of the plug; a cylinder of conducting material in telescoping relation with the body and bearing against a length of the fusible element at the said other end thereof; a perforated plate of insulating material; and a contact post of conducting material fitted through the perforation of the plate, into the other bore and into engagement with the fusible element, the said other end of the fusible element having an annulus thereon to circumscribe a part of the outer portion of the plug, the said one end of the fusible element being a head thereon provided with an opening to receive the contact post.

5. A fuse plug of the character described comprising a hollow body of insulating material; a plug of insulating material projecting into the hollow body and provided with two intersecting bores; a fusible element partially circumscribing the plug and having one end thereof extending into one bore of the plug and the other end disposed against the outer portion of the plug; a cylinder of conducting material in telescoping relation with the body and bearing against a length of the fusible element at the said other end thereof; a perforated plate of insulating material; and a contact post of conducting material fitted through the perforation of the plate, into the other bore and into engagement with the fusible element, said plug having a boss on the outer end thereof, the said other end of the fusible element having an annulus thereon to circumscribe the boss, the said one end of the fusible element having an opening to receive the contact post.

6. A fuse plug of the character described comprising a hollow body of insulating material; a plug of insulating material projecting into the hollow body and provided with two intersecting bores; a fusible element partially circumscribing the plug and having one end thereof extending into one bore of the plug and the other end disposed against the outer portion of the plug; a cylinder of conducting material in telescoping

relation with the body and bearing against a length of the fusible element at the said other end thereof; a perforated plate of insulating material; and a contact post of conducting material fitted through the perforation of the plate, into the other bore and into engagement with the fusible element, said plug having a boss on the outer end thereof, the said other end of the fusible element having an annulus thereon to circumscribe the boss, the said one end of the fusible element having an opening to receive the contact post, said cylinder having an internal flange overlying the annulus of the fusible element and circumscribing the boss on the plug, said plate being held against the flange of the cylinder by the contact post.

7. A fuse plug of the character described comprising a hollow body of insulating material; a plug of insulating material projecting into the hollow body and provided with two intersecting bores; a fusible element partially circumscribing the plug and having one end thereof extending into one bore of the plug and the other end disposed against the outer portion of the plug; a cylinder of conducting material in telescoping relation with the body and bearing against a length of the fusible element at the said other end thereof; a perforated plate of insulating material; and a contact post of conducting material

fitted through the perforation of the plate, into the other bore and into engagement with the fusible element, said plug having a boss on the outer end thereof, the said other end of the fusible element having an annulus thereon to circumscribe the boss, the said one end of the fusible element having an opening to receive the contact post, said cylinder having an internal flange overlying the annulus of the fusible element and circumscribing the boss on the plug, said plate being held against the flange of the cylinder by the contact post, said plug having an external flange resting on the lip of the thimble, said thimble and cylinder being in screw-threaded engagement.

8. As a new article of manufacture, a fusible element for fuse plugs, comprising an elongated body; an annulus formed at one end of the body; and a nut secured to the other end of the body.

9. In a fuse plug of the character described, a plug provided with two intersecting bores; a fusible element partially circumscribing the plug with one end projecting into one of the bores; a threaded contact post projecting into the other bore; and a nut carried by the said one end of the fusible element, in screwthreaded engagement with the contact post.
